UNITED STATES PATENT OFFICE.

GEORGE McFADDEN, OF NEW YORK, N. Y.

STRIKING-BAG FRAME.

SPECIFICATION forming part of Letters Patent No. 658,553, dated September 25, 1900.

Application filed March 27, 1900. Serial No. 10,337. (No model.)

To all whom it may concern:

Be it known that I, GEORGE McFADDEN, a citizen of the United States, and a resident of the city, county, and State of New York, 5 have invented certain new and useful Improvements in Striking-Bag Frames, of which the following is a full, clear, and exact specification.

This invention relates to striking - bag frames particularly designed for home use, the object of the invention being to provide a frame of simple and durable construction, easily adjustable to any desired height, and portable in its nature.

15 A striking-bag frame constructed in accordance with my invention is illustrated in the accompanying drawings, in which—

Figure 1 is a perspective view of a door-frame having my device secured thereto. 20 Fig. 2 is a side elevation of one of the arms. Fig. 3 is a view of a receiver, and Fig. 4 is a detail side view of the cross-piece from which the bag may be suspended.

In making a frame in accordance with my 25 invention I secure one arm A to each side of a door-jamb or other permanent object by means of combination-screws. The arms A are hinged in the center in order that they may be readily folded, and at each side of the 30 hinge a I place screw-holes b, through which one end of the combination-screw passes, and the arms are then prevented from moving by screwing a nut or the like over the projecting screw-thread. At or near each end of the 35 arms A are openings or apertures c, through which the hook d of the receiver B passes. Any desired number of these receivers may be stretched between the arms, the force with which the bag rebounds being regulated by 40 the number of receivers employed.

The bag C may be suspended either from the top of the door-frame, as would be convenient for a person of average height, or it

may be suspended from a cross-piece D, each end of which fits into mortises in the arms 45 A, and said cross-piece may be placed at any desired height to suit the convenience of the user.

A frame as above described is exceedingly simple in construction and, being easily 50 adjustable, portable, and readily folded into a small compass, is much superior to articles of similar nature now in use.

Having described my invention, what I claim as new, and desire to secure by Letters 55 Patent, is—

1. A striking-bag frame comprising a pair of bars extending parallel with each other, means arranged centrally of said arms by which they may be secured to the door-jamb, 60 and a plurality of receivers at each end of the bars extending parallel with each other between the bars and at right angles thereto.

2. A striking-bag frame comprising a pair of parallel arms each composed of hinged sections and receivers secured to the arms and extending transversely between them, the 65 hinges of the arms being arranged centrally thereof.

3. A striking-bag frame comprising a pair 70 of centrally-hinged arms, means for securing said hinged arms to a stationary object, and receivers at each end of said arms, substantially as described.

4. The combination in a striking - bag 75 frame, of a pair of centrally-hinged arms, a cross-piece fitting into mortises in said arms, and means for securing said arms to a permanent object, substantially as described.

In witness whereof I have hereunto set my 80 hand in presence of two witnesses.

GEORGE McFADDEN.
